(**) Term: **14 Years**

(57) **CLAIM**

(21) Appl. No.: **29/273,273**

We claim the ornamental design for cook-top for induction oven range, as shown and described.

(22) Filed: **Mar. 2, 2007**

DESCRIPTION

(30) **Foreign Application Priority Data**

Sep. 15, 2006 (KR) 30-2006-0038155

FIG. 1 is a perspective view of cook-top for induction oven range showing the new design:

(51) **LOC (8) Cl.** **07-02**

FIG. 2 is a front elevation view thereof;

(52) **U.S. Cl.** **D7/346**

FIG. 3 is a rear elevation view thereof;

(58) **Field of Classification Search** D7/323,

FIG. 4 is a left-side elevation view thereof;

D7/339-348, 402-408; 219/391-392, 395,

FIG. 5 is a right-side elevation view thereof;

219/445-446, 446.1, 460.1, 560; 126/198,

FIG. 6 is a top plan view thereof; and,

126/211, 39 B, 19 R, 39 C, 50, 39 R, 273 R

FIG. 7 is a bottom plan view thereof.

See application file for complete search history.
